(57) **CLAIM**

The ornamental design for a gripable sleeve for sliding collet assembly, as shown and described.

DESCRIPTION

FIG. 1. is a top, right, elevational, perspective view of a gripable collar for sliding collet assembly according to the present invention;

FIG. 2. is a top plan view thereof;

FIG. 3. is a bottom right perspective view thereof;

FIG. 4. is a bottom plan view thereof;

FIG. 5. is a right side, elevational view with the left side elevational view being a mirror image thereof; and,

FIG. 6. is a front elevational view with the rear elevational view being a mirror image thereof.
